UNITED STATES PATENT OFFICE.

EMILIO CARDARELLI, OF BOSTON, MASSACHUSETTS.

EXTENSION STEPLADDER.

Application filed May 15, 1923. Serial No. 639,102.

To all whom it may concern:

Be it known that I, EMILIO CARDARELLI, a citizen of the United States of America, and resident of Boston, in the county of Suffolk and State of Massachusetts, have invented new and useful Improvements in Extension Stepladders, of which the following is a specification.

This invention relates to combined step and extension ladders.

Principal objects of the invention are to provide a ladder of the type specified which, while light in weight, is very stiff and strong whether employed as a step or extension ladder; to provide locking means of simple and reliable character for holding the ladder sections in relatively adjusted position; to provide an improved connection between the ladder sections permitting them freely to swing to form a step ladder and constituting a brace when the sections are extended.

A preferred embodiment of the invention is illustrated in the accompanying drawings in which,—

25 Fig. 1 is a front elevation of the ladder positioned for use as a step ladder;

Fig. 2 is a vertical section through the ladder arranged as in Fig. 1;

30 Fig. 3 is a vertical section showing the parts in position to constitute an extension ladder;

Fig. 4 is a horizontal section on the line 4—4 of Fig. 3;

35 Fig. 5 is a horizontal section on the line 5—5 of Fig. 3, and

Fig. 6 is a horizontal section on the line 6—6 of Fig. 3.

The front or main section of the ladder is indicated at 1. This front section comprises 40 the side rails 2, 3 supporting the steps 4. Preferably the side rails 2, 3, converge toward the upper end of the section. The upper step 5 of the front section is preferably wider than the others as is usual in 45 step ladder construction.

A hinge device is secured to one of the upper steps of the front section, as for example the step 4^a. This hinge device comprises the fixed leaf 6 secured in any desired 50 manner to the under side of the step 4^a. A swinging leaf 7 is secured to the fixed leaf by means of a pintle pin 8. This swinging leaf is provided with spaced rearwardly extending members 9, 10 which are furnished 55 with the inwardly directed portions 11, 12

respectively, thus constituting a guide for the rear or extension section 13 of the ladder.

This extension section comprises the substantially parallel side rails 14, 15 which support the steps 16. A locking device 17 is secured to the lower part of the section 13. This locking device preferably comprises a metallic rod bent to bail-like form and pivotally connected at its end portions to the respective side rails 14, 15. This locking member 17 is adapted to overlie a step of the front section of the ladder and its middle portion is bent as indicated at 18 to engage the front edge of such step, thereby securely holding it in position. As the side rails of the rear section slide freely in the guide carried by the swinging leaf of the hinge device, it is possible to extend the rear section as indicated in Fig. 3 to any desired degree, the bail-like locking device being engaged with a selected step of the front section to retain the parts in adjusted position.

Preferably the swinging leaf 7 of the hinge device is furnished with a forwardly projecting stop 7^a which is engageable with the under surface of the fixed leaf 6 to limit movement of the swinging leaf in one direction. Thus when the section 13 is fully extended any tendency to swing such section rearwardly about its lower end as an axis is resisted by such stop device.

The uppermost step of the rear section 13 is preferably provided with a swinging arm or bracket 19 secured to the under surface of the step by means of a bolt 20. This bracket normally lies below the uppermost step of the extension section, but when desired may be swung at right angles thereto as indicated in dotted line in Fig. 2. This bracket terminates in a hook 21 in which a bucket or other utensil may be hung. As this hooked bracket is carried by the rear section it is available for use whether the parts are disposed to form a step ladder or an extension ladder.

Stop members 22, 23 are carried by the side rails 14, 15 respectively at a point above the uppermost step 16. These stop elements preferably consist of screws inserted from the inner sides of the respective rails and projecting laterally therefrom to such a distance that when the extension member is drawn downwardly, the screws overlap and contact with the elements 9, 10 respectively.

of the swinging guide, thus limiting downward movement of the extension section. These screws may, however, be retracted sufficiently to permit complete downward withdrawal of such section from the guide, if desired.

The front section of the ladder is provided with a pair of substantially parallel elongate fixed guide rails 24, 25, secured to its rear side. These rails project rearwardly and are furnished with inwardly directed portions 26, 27, respectively, thus providing a pair of parallel oppositely disposed guide channels extending longitudinally of the front section of the ladder. These guide channels are adapted for the reception respectively of laterally projecting lugs 28, 29 at the lower part of the rear section 13 of the ladder. These lugs conveniently consist of the projecting ends of the bail-like locking device 17, although lugs of other form or construction may be employed if desired. The guide rails 24, 25 terminate at a point short of the lower end of the front section of the ladder so that upon swinging the ladder sections into substantial parallelism the lugs 28, 29 may be entered within the respective guide channels. As the rear or extension section of the ladder is moved upwardly these lugs slide within the channels so that the lower end of the ladder is prevented from swinging rearwardly relatively to the front section, while the engagement of the lugs with the mem-

bers 9, 10 limits the upward movement of the rear section. The ladder sections are thus very securely held in substantial parallelism when extended so that an extremely stiff construction is provided without increasing the weight of the ladder to any substantial degree.

I claim:

1. A ladder of the class described having a front section having a hinge device secured thereto, said hinge device comprising a swinging leaf provided with a guide, a rear section sliding in said guide, and a stop carried by the swinging leaf and engageable with a fixed part of the front section to limit movement of said leaf with its guide.

2. A ladder of the class described comprising a front section having steps, a hinge device secured to an upper step of said section, the hinge having a swinging leaf provided with a stop engageable with the under side of said upper step to limit swinging movement of the swinging leaf in one direction, a guide carried by said swinging leaf, a rear ladder section sliding in the guide, and a locking member carried by the rear section and engageable with steps of the front section to hold the sections in selected positions of adjustment.

Signed by me at Boston, Massachusetts, this twelfth day of May, 1923.

EMILIO CARDARELLI.
